UNITED STATES PATENT OFFICE.

FRANK D. LAMBIE, OF UPPER MONTCLAIR, NEW JERSEY, ASSIGNOR TO LAMBIE BROTHERS CORPORATION, A CORPORATION OF NEW YORK.

MOLD FOR BUILDING MONOLITHIC HOUSES.

1,122,772.

Specification of Letters Patent. Patented Dec. 29, 1914.

Application filed March 7, 1914. Serial No. 823,101.

To all whom it may concern:

Be it known that I, FRANK D. LAMBIE, a citizen of the United States, residing at Upper Montclair, in the county of Essex and State of New Jersey, have invented certain new and useful Improvements in Molds for Building Monolithic Houses, of which the following is a full, clear, and exact description.

10 This invention relates to molds for building concrete houses and the like and has for its general object the provision of a knock down mold composed of metal forms or mold plates which may be assembled to receive 15 the concrete for casting one complete story of the building including a floor at a single pour or cast.

In my application Serial No. 779,267, filed July 16, 1913, I have disclosed a mold 20 consisting of an exterior frame built up of separable units rigidly secured together in the form of a hollow rectangle which frame surrounds an interior frame consisting of separable units also rigidly united together and having substantially the form 25 of an inverted box, the concrete when poured filling the space between the walls of the two frames and spreading over the top of the interior frame to form the walls and 30 floor of the building.

The present invention relates to molds of this general character and has for its principal object the provision of an interior mold, which, when assembled and the concrete floor has been cast, may be removed 35 in an entirely simple and expeditious manner and accordingly the invention contemplates the use of horizontally disposed plates which are secured to the top of the wall 40 plates of the interior frame and against which the ceiling plates abut with the surfaces of both plates substantially flush. The lower ends of the ceiling plates are therefore above the upper ends of the wall plates, so 45 that when the wall plates are disconnected they may be readily removed.

Another object of the invention is to provide a construction whereby the major portion 50 of the wall plates of the interior frame may be removed while a sufficient number of them are permitted to remain in posi-

tion to support the ceiling plates. This construction provides means for supporting the concrete floor, and yet permitting the major portion of the wall plates to be used in the 55 construction of the other stories of the building, for since the floor is subjected to shearing stresses, it need necessarily be supported for a longer period of time than the walls.

Another object of the invention is to provide a mold having its exterior and interior frames so constructed that the greater part of the wall plates of both the exterior and interior frames may be removed after the 60 concrete wall for the first story has set and thereafter the same plates be utilized in the 65 construction of the other stories of the building.

Other objects of the invention will hereinafter appear and the novel features thereof are pointed out in the appended claims.

In the drawings, Figure 1 is a front elevation of a mold frame for completing one story of a two-room house constructed in accordance with the principles of my invention; Fig. 2 is a plan of the same; Fig. 3 is an enlarged detail showing a transverse vertical section through the exterior and interior frames at the upper ends of the same and also showing the manner in which the 75 inner mold frame is released; and Fig. 4 is an enlarged horizontal section through a corner of the mold frame.

As disclosed in my application Serial No. 779,267 referred to, the exterior frame which 80 has substantially the form of a hollow rectangle, is composed of standard plates which are broadly designated 1. Each of these plates comprise a relatively long and narrow strip of channel-iron of a height to form the 85 wall for one story of the building. Riveted to the inner faces of the channel irons at the ends thereof are the right-angled L's 2, the projecting legs of which are flush with the ends 90 of the channel irons forming a field plate 95 having a projecting marginal flange flush with its edges. The integral flanges of the channel iron and the L's 2 are made sufficiently strong to withstand the crushing and bending strains to which they are subjected in ordinary use. At suitable intervals in the side flanges of each of the plates

are square apertures which register with each other when the plates are vertically-disposed with their flanges abutting and their ends substantially flush. These apertures receiving the clips 3 which are provided with openings in their shanks, into which the wedges 4 are driven, drawing the flanges of the plates together to form a tight joint between the same. Substantially L-shaped notches 5 are cut in each of the side flanges near their upper and lower ends, into which liner locks 6 fit, the liner locks consisting of rigid strips of angle-irons of the proper length to engage the notches in a plurality of plates, thus alining the plates and rigidly holding them against displacement. The plates at the corners of the exterior frame are joined together by L's 7 which are provided with apertures and clipped to the flanges of these plates as has been described.

The end flanges of the standard plates have square apertures 8 and 9 therein (see Fig. 4) which are arranged in transverse alinement but at different distances from the surface of the plate. Horizontally-disposed belting course plates 10 are superposed upon the vertically-disposed wall plates 1, which plates are constructed similarly to the standard wall plates, 1, and have apertures in their side flanges which are adapted to be brought into registry with either of the square apertures 8 or 9 in the top flanges of the wall plates and secured thereto by clips and wedges, whereby an offset of a belting course flush with the surface of the concrete wall may be obtained. Where an offset belting course is desired, a flat strip of metal 11, is interposed between the top of the wall plates and the belting course plates (see Fig. 3) and serves to prevent the concrete from flowing through the square aperture 9 and forming irregularities in the concrete walls.

Pilaster corners are formed by the construction disclosed in Fig. 4, wherein 12 designates a plate of a special form which is used whenever a pilaster corner is desired, this plate being of less width than the standard wall plates and having riveted to one of its side flanges a strip of iron 13 which projects considerably beyond the edge thereof and is provided with square apertures 14. Standard plates 15 are arranged with their apertures in alinement with the apertures 14 and are clipped and fastened to the plates 12 in the usual manner, the surfaces of the plates being thus offset from the surface of the plate 12 a sufficient distance to give the pilaster effect. The end flanges of the plate 12 are provided with square apertures 16 and the corner plates are provided with similar apertures 17 which are so arranged that the apertures in the side flanges of the belting course plates 10 which occur at regu-

lar intervals will register with the same when the belting course plates are superposed thereon, whereby the belting course plates may be fastened in place by clips and wedges as has been described.

The exterior frame is rigidly supported against spreading or lateral displacement by sectional tie-rods 20 extending transversely and longitudinally of the frame and connecting the opposite sides thereof, the sections of the tie-rods being connected together by the tie-blocks 21. Turn buckles 22 are interposed between sections of the tie-rods whereby the rods may be tightened after the frame has been completely set up. Short length sections 23 forming part of tie-rods 20 extend through openings in the belting course plates 10 and are threaded to receive nuts 24 which secure the belting course plates in place, the short length sections preferably being surrounded by sleeves 25 which prevent the concrete from forming around the short length sections and permit the same to be backed out of the wall after the concrete has set, thus leaving an opening in the concrete wall which may be filled after the house is completed. As is clear from Fig. 3, the tie-rods 20 are located just above the top of the ceiling plates, which will be later referred to, and upon the casting of the walls and floor of the house, the tie-rods 20 will be permanently embedded in the concrete floor and thus act as a reinforcement for the same. The tie-rods 20 and nuts 24 also will rigidly maintain the belting course plates 10 in position and the wall plates 1 which heretofore have been necessary to support the belting course plates may be removed and superposed upon the belting course plates to form the next story of the building, as will be hereinafter referred to in the description of the assembling of the mold. In practice the tie-rods 20 are preferably spaced about three feet apart which has been found to be adequate to rigidly hold the exterior frame against lateral displacement the greater number of the tie-rods being omitted from the drawing but holes 20' for the same are shown in the belting course plates. (See Fig. 1).

The interior mold frames which are separately assembled for each room of the house form a bearing wall between the rooms, as will be apparent from Fig. 2. The wall frames are composed of vertically-disposed standard wall plates 1', of the same construction and size as those used in the construction of the exterior mold, which have registering apertures through which the clips 3 are passed and the plates secured together by the wedges 4. Located at the corners of each frame are corner plates 26 which are provided with marginal flanges similar to those of the standard wall plates. These corner plates as well as the standard

plates used in the construction of the interior mold, are each provided with L-shaped notches near their upper and lower ends for the reception of liner locks 27 similar to those used in the exterior frame. As each of the standard plates in a straight line is locked to a corner plate, a rigid self supporting structure having substantially the form of a rectangular box open at the top and bottom, is formed which will not require any further means for rigidly sustaining the structure other than the liner locks and the clips. If it is desired a space for a chimney may be left as indicated at 29 which is formed by using inside corner angle plates 30 and 31 and standard plates 32, these plates being locked and fastened together in the usual manner. Before casting the concrete, a core for the chimney consisting of fire tiling (not shown) would be emplaced in the space 29 which fire tiling is adapted to remain permanently embedded in the concrete.

The ceiling of the inner frames is supported by means of eye-beams or channel irons 33 the ends of which are adapted to rest on the upper row of liner locks 27, to which they are secured by the stud bolts 27' wedges 33 being preferably interposed between the bottoms of the L-beams and the liner locks 27 to facilitate in the removal of the ceiling plates and the eye-beams as will be later referred to. Upon the supports 32 are laid standard plates 1" which are arranged with their flanges abutting to form the top of the inverted box.

Release plates 35 which are adapted to be positioned on the tops of the wall plates 1" consist of straight U-shaped strips of metal, one leg 36 of which is considerably longer than the other leg 37. Apertures are provided in the short leg 37 which are adapted to register with the apertures in the top flanges of the wall plates of the interior frame whereby the release plates may be clipped and fastened thereto in the usual manner. These release plates are formed in strips of proper length to accurately fit around the top surface of the wall plates 39 the long leg of the U-shaped pieces extending inwardly beyond the edges of the top flanges of the wall plates. (See Fig. 2.) Where it is necessary to form irregularities in the interior frame, to provide for a chimney, chimney release plates 38, 39 and 38' are necessary which are clipped and fastened in place in the same manner. The ceiling plates 1" are arranged abutting the release plates to form the top of the box over which the wet concrete is caused to form the floor of the building, and as the surfaces of the release plates and ceiling plates are substantially flush, the flanges of the ceiling plates are above the level of the top 65 of the wall plates and so will not interfere

with the disassembling of the mold, as will be later referred to.

The interior and exterior frames are provided with door and window openings 39 and 39', respectively, the door opening being surrounded by door plates 39" which form a box, and the space between the frames and surrounding window opening 39' being filled by a wooden window frame (not shown) which serves as a part of the mold for shaping the window opening as has been disclosed in my application Serial No. 822,741 filed March 5, 1914. Interposed between the bottoms of the wall plates forming the exterior frame and its supporting structure, are the footing course angles 40 consisting of right angle L's made of iron or other suitable material upon which the plates rest. The interior plates also rest on similar footing course angles 41, the footing course angles for the second story of the building being shown in section in Fig. 3.

The method of constructing the mold frame is to assemble the interior casing before the exterior wall frame is placed in position. First the footing course angles 41 are laid upon the footing course and leveled up forming a rectangle of a size corresponding to the desired house with the upstanding legs of the L's facing inwardly. Preferably an inside corner plate 26 is first placed in position and the standard plates 1 are then placed upon the footing course L's with the surfaces of the plates facing outwardly. Liner locks 27 are positioned in the notches in the top and bottom of the plates which will insure that the outer surfaces of the plates are in exact alinement and will lock the plates to the corner plates and prevent any lateral movement thereof. Clips 3 are then driven through the registering apertures in the abutting flanges of the plates and the plates securely locked together by the wedges 4, the other sides of the interior frame being assembled in the same manner to form a rigid box open at the top and bottom which needs no additional supporting means to insure its rigidity. The exterior frame is assembled in the same manner, the footing course angle L's 40 being leveled up and the standard plates 1 assembled thereon. The standard plates are of uniform size and the plates in the exterior frame are arranged opposite and in exact alinement with the wall plates of the interior frame. In the construction shown in Fig. 4, the special plates 12 are used for forming the pilaster, which plates are of a width sufficiently greater than the corner plate 26 of the interior frame to provide the necessary offset for the pilaster and yet maintain the other plates of the frame in alinement. After the wall sections of the exterior frame have been properly set up the bedding course plates 10 are secured

thereto and the tie-rods 20 are placed in position which firmly secures the opposite sides of the exterior frame together providing a rigid exterior frame which is supported entirely independently of the interior casing, there being no tie-rods or other devices connecting the walls of the frames at short intervals which are at present used in the construction of mold frames of this character. The release plates 35 are then secured to the top of the wall plates of the interior frame and the supports 32 are placed in position, and the ceiling plates are laid thereon forming a self-supporting rigid structure having the form of an inverted box which, together with the exterior frame, is now completely assembled to cast one complete story including the floor, of a building at a single pour. The concrete is then poured into the space between the interior and exterior frames and spread in a layer over the ceiling plates to a level flush with the upper flanges of the belting course plates 10 where it is troweled off. The concrete is then allowed to set for a sufficient period of time for the walls to become sufficiently rigid to sustain the compression stresses and strains to which it is subjected. Since the tie-rods 20 are now permanently embedded in the concrete, the standard plates forming the first story of the building are no longer necessary to support the belting course plates and they may be removed by backing off the footing course angles 40 which will release these plates from engagement with the belting course plates at their upper ends and they may be readily removed by taking out the liner locks and knocking out the clips 3. The belting course plates 10, however, remain rigidly fastened to the concrete wall by means of the tie-rods 20 and nuts 24. To construct the second story of the house, these mold plates may be superposed upon the belting course plates and clipped and fastened thereto in the manner which has been described. Since the holes in the side flanges of the belting course plates 10 are arranged at the same distance from its surface, the second row of mold plates will be automatically lined up with the outer surface of the concrete wall of the first story, as will be clear from Fig. 3. It is therefore to be observed that in the construction of a building of more than one story, the same set of standard wall plates may be used for the construction of the exterior frame for all of the stories, it being necessary only to provide a number of sets of belting course plates. This feature is of decided importance since the forms or molds plates are made of steel and are therefore expensive, so that if an entirely separate set of mold plates need be provided for constructing the

several stories of the building, the cost of 65 the building would be increased two or even more times.

Since the floor of a concrete building is subjected to shearing as well as compression stresses and strains, it is necessary that 70 it be supported for a longer period of time than the walls of the building. The majority of the wall plates composing the interior frame are removed without disturbing the ceiling plates which support the concrete floor in the following manner: The upper liner locks 27 which carry the channel supports or eye-beams 32 are separate from the liner locks connecting the other plates and are of a length slightly less than the width of a plate, therefore serving merely as a support for the eye-beams. The footing course L's 41 beneath the wall plates which support the eye-beams 32 are also 75 independent of the other footing course L's. 80 When the wall plates of the interior frame are to be removed, the footing course L's 41, with the exception of those beneath the wall plates which support the eye-beams 32, are backed off and the wall plates and release 85 plates supported thereby are permitted to drop out of supporting engagement with the concrete floor. The release plates 35 are then disconnected from the wall plates and from each other, the liner locks 27 and the 90 clips and wedges being removed. Each of the wall plates may then be drawn out laterally until its outer upper edge clears the inner lower edge of the release plates and since the ceiling plates are slightly above 95 the level of the top of the wall plates, the latter may be tilted on the inner edge of the bottom flange without striking against the ceiling, which remains undisturbed to support the concrete floor. Where possible, it 100 is preferable to support the eye-beams 32 from wall plates other than corner plates so that the latter may be removed and used in the construction of the next story of the building. After the concrete floor has 105 fully set, the ceiling plates and supporting wall plates may be removed, the wedges 33 between the eye-beams 32 and the liner locks 27 being removed before the ceiling plates to afford more play between the ceiling plates and the concrete ceiling.

I claim:

1. In a knock down mold for constructing one complete story of a monolithic building including a floor, an interior mold frame comprising a plurality of separate mold plates rigidly secured together and having the form of an inverted box, means including several of said wall plates for supporting the top plates of the box, said wall plates being removable independently of each other and of the ceiling plates whereby the top plates of the box and the wall plates

- supporting the same may remain in position after the other wall plates have been removed, said last-named plates being of sufficient strength to support the ceiling.
5. 2. A knock down mold for constructing one complete story of a monolithic building, an interior mold frame composed of vertically-disposed wall plates, means for rigidly securing said plates together, a plurality of ceiling plates, cross-beams for supporting the latter, means for supporting said beams including several of the wall plates, removable strips interposed between said wall plates and their supporting structure, the strips beneath the wall plates for supporting the ceiling plates being independent of the other strips whereby when said strips are removed from beneath the wall plates with the exception of those which support the ceiling plates, the wall plates other than those which support the cross-beams may be removed without disturbing the ceiling plates.
3. In a knock down mold for constructing one complete story of a monolithic building, an interior frame composed of a plurality of flanged mold plates, means passing through said flanges for securing said plates together, liner locks for rigidly locking said plates against lateral movement, said liner locks comprising metallic strips uniting a plurality of plates, cross-beams supported by said liner locks, ceiling plates supported by said cross-beams, and removable strips interposed beneath said wall plates and their supporting structure, the liner locks for supporting the cross-beams being independent of the remaining liner locks and the strips beneath the wall plates which support the cross-beams being independent of the strips beneath the remaining wall plates, whereby the wall plates other than those for supporting the ceiling plates may be removed without disturbing the supports for the ceiling plates.
4. In a knock down mold for constructing one complete story of a monolithic building including a floor, an interior mold frame composed of vertically-disposed wall plates, ceiling plates, means for supporting the ceiling plates above the level of the top of the wall plates, and release plates secured to the top of the wall plates having their surfaces substantially flush with the surfaces of the ceiling plates.
5. In a knock down mold for constructing one complete story of a monolithic building including a floor, an interior mold frame having the form of an inverted box and comprising vertically-disposed wall plates, ceiling plates, said plates consisting of rectangular plates having marginal flanges and adapted to be interchanged, release plates comprising U-shaped channel irons secured to the tops of the wall plates, and means for supporting the ceiling plates with their surfaces substantially flush with the upper surfaces of the release plates, said ceiling plates being above the level of the top of the wall plates.
6. In a knock down mold for constructing one complete story of a monolithic building including a floor, an interior mold frame comprising a plurality of separate mold plates rigidly secured together and having the form of an inverted box, means including several of said wall plates for supporting the top plates of the box, some of said wall plates being removable independently of the others and the ceiling plates whereby the top plates of the box and the wall plates for supporting the same may remain in position after the other wall plates have been removed, an exterior frame also composed of separate mold plates rigidly secured together, belting course plates extending across several of said last named wall plates and secured thereto and means adapted to be permanently embedded in the concrete floor when the concrete is cast, whereby the belting course plates will remain supported in position against the surface of the concrete walls and the wall plates may be removed and again superposed upon the belting course plates.
7. A knock down mold for constructing one complete story of a monolithic building, comprising an interior mold composed of vertically disposed flanged rectangular standard plates, means for securing said plates together, a plurality of horizontally disposed flanged rectangular standard plates forming the ceiling, means including several of said wall plates for supporting said horizontally disposed plates with their flanges above the level of the upper edges of said wall plates whereby the wall plates other than those which sustain the horizontally disposed plates may be removed without disturbing the latter.
8. A knock down mold for constructing one complete story of a monolithic building, comprising an interior mold composed of vertically disposed flanged rectangular standard wall plates, means for securing said plates together, a plurality of horizontally disposed flanged rectangular standard plates forming the ceiling, cross beams supported by some of said wall plates and arranged to support said horizontally disposed plates with their flanges above the upper edges of said wall plates, whereby said wall plates other than those which sustain the ceiling plates may be removed without disturbing the latter.
9. A knock down wall for constructing one complete story of a monolithic building, including the floor, an interior mold frame

composed of vertically disposed wall plates, ceiling plates, cross beams supported by some of said wall plates for sustaining said ceiling plates above the level of the top of 5 said wall plates, and plates secured to the top of said wall plates abutting said ceiling plates and having their surfaces adjacent the line of jointure with said ceiling plates substantially flush with the surfaces of said 10 ceiling plates whereby said wall plates other

than those which sustain the ceiling plates may be removed without disturbing the latter.

In witness whereof I subscribe my signature, in the presence of two witnesses.

FRANK D. LAMBIE.
